UNITED STATES PATENT OFFICE.

FREDERICK L. MCGAHAN, OF LOS ANGELES, CALIFORNIA; VIOLA K. WALKER, ADMINISTRATRIX OF SAID FREDERICK L. MCGAHAN, DECEASED, ASSIGNOR TO THE PURPOSED MIND DEVELOPMENT SECURITY ASSOCIATION OF THE WORLD, A TRUST COMPANY.

SUCTION MEANS FOR FEEDING POWDERED FUEL TO FIRE BOXES.

Original application filed January 3, 1918, Serial No. 210,146. Divided and this application filed January 17, 1919. Serial No. 271,713.

To all whom it may concern:

Be it known that I, FREDERICK L. MCGAHAN, a citizen of the United States, residing at the city of Los Angeles, in the county of 5 Los Angeles and State of California, have invented certain new and useful Improvements in Suction Means for Feeding Powdered Fuel to Fire Boxes, of which the following is a specification.

10 This application is a division from the application of the same inventor for patent for locomotive filed January 3, 1918, Serial 210,146 which matured into Patent 1,292,399, January 21, 1919, and relates more particularly to the suction means for drawing powdered fuel into the locomotive fire-box.

15 In the accompanying drawings forming part of this specification, in which like numbers of reference denote like parts wherever 20 they occur,

Fig. 1 is a fragmentary side elevation of the tender end of the locomotive, showing the fire-box in section and the turbine that is actuated from the exhaust steam of the 25 turbine that drives the suction fan, in dotted lines.

Figure 2 illustrates the fire-box and is a sectional view taken on the line 2—2 in Figure 1;

30 Fig. 3 is a fragmentary elevation of the smoke box end of the locomotive with parts broken away to show the fire tubes and smoke box, the turbine for operating the suction fan being shown in dotted lines.

35 Fig. 4 is a longitudinal sectional view of the turbine and suction fan for drawing the powdered fuel into the fire-box.

The present invention relates to fuel feeding devices for locomotives and consists 40 of the combination, arrangement and organization of elements to be herein described in detail. The locomotive, as shown in Fig. 1, is equipped with the usual boiler 58 having at its rear end a fire box 8 and at its front

45 end a smoke box 56. The steam generated in the boiler is supplied to the driving engines of the locomotive in the usual way. The steam exhaust from the cylinders 55 of the ordinary main driving mechanism of a 50 locomotive passes through pipes 3 into the casing 4 of the turbine 1 and rotates the turbine and therewith shaft 5, to which is fixed

at one end pinion 6, and at the opposite end fan 2. (See Fig. 4.) Thus when the ordinary driving mechanism of the locomotive 55 is working, the turbine 1, as an auxiliary driving mechanism for driving the wheels 65, is also in operation, and fan 2 is being constantly rotated with the result that the same exerts suction through inlets 7 of the 60 turbine 1 within the smoke box 56 and this suction is communicated through the fire-tubes 57 to the fire-box 8.

The said suction draws powdered fuel out of the nozzles 10, extending through the sides 65 of the fire box (see Figs. 1 and 2), of which there are preferably two, (one entering fire-box 8 from each side thereof). This powdered or pulverized fuel being drawn, as just stated, within fire-box 8, strikes the 70 tapering walls of arch 11 and is thereby deflected upwardly into the upper part of the fire-box, in which operation ridge 12 assists, whereby the pulverized fuel is scattered throughout the fire-box, resulting in quicker 75 and more certain and complete combustion and consequent heating of the fire tubes 57.

Any cinders will be drawn by the said suction through inlets 7 into the interior chamber 13 within turbine 1, whence they are 80 passed through openings 14 and exhaust pipes 15 for return passage to ultimate deposition in hopper 16, whence the said cinders drop into conveyor 17, containing the screw 18 for force-feed, together with other 85 comminuted fuel from the tender 19 of the locomotive, there being slots in the floor of the said tender (which slots are not shown in the drawings) which allow pulverized fuel to flow out of the tender into the conveyor 17.

The said force-feed 18 may be used in combination with the said suction means that more particularly forms the subject-matter of this patent, or either may be used 95 separately.

The screw 18 is driven by shaft 20, of the turbine 60 (see Fig. 1) which is provided with gear connection 21 with gear 22, which is mounted on or driven by axle 23.

The mechanism intermediate pipe 24 that leads into hopper 16 is fully described in the said patent, but is omitted from this case as forming the subject-matter of another di-

visional application filed simultaneously herewith. The turbine 60 is driven by the exhaust steam from the turbine 1, as described in my Patent 1,292,399.

As fully disclosed in the said patent, the action of the turbine 1, fan 2, and screw 18 is continuous while the locomotive is traveling and thereby suction is continuously exerted out of fire-box 8 through inlets 7 within 5 the smoke box 56 which communicates with the fire-box 8 through the fire tubes 57, as before described, thus drawing pulverized fuel through nozzles 10 to which pipes 25 lead. Pipes 25 are connected with conveyor 15 17 by their telescopic arrangement with pipes 26 and flexible joints 27. It will be understood that conveyors 17 are preferably duplicated on opposite sides of the tender and that the same are necessary whether a 20 screw 18 be contained therein or not, and that joints 27, pipes 26, pipes 25, and nozzles 10 are also in pairs upon opposite sides of the tender, thereby enabling the discharge 25 into fire-box 8 of powdered fuel from opposite sides of the said fire-box as clearly shown in Figure 2.

Having thus described this invention, I hereby reserve the benefit of all changes in form, arrangement, order, or use of parts, as it is evident that many minor changes 30 may be made therein without departing from the spirit of this invention or the scope of the following claim.

I claim:

In a locomotive, the combination of a fire-box, a source of pulverized fuel connecting therewith having nozzles for the said fuel communicating with the interior of the said fire-box, suction means for drawing the fuel, from the said nozzles into the fire-box, 35 said suction means comprising a rotatable member having a chamber therein, means for admitting steam into the said chamber, means for carrying smoke, cinders, and sparks from the fire-box to and into the said 40 chamber, means for causing the revolving of the said chambered member, thereby mixing the said smoke and steam, and means for exhausting from the said chamber. 45

In testimony whereof I hereunto affix my 50 signature.

FREDERICK L. McGAHAN.
